SHAMPOOS

Armin Hiestand, Binningen, Switzerland, assignor to Ciba Limited, Basel, Switzerland, a Swiss company
 No Drawing. Filed June 22, 1965, Ser. No. 466,061
 Claims priority, application Switzerland, Oct. 25, 1961,
 12,333/61
 14 Claims. (Cl. 252—152)

This is a continuation-in-part of application Ser. No. 232,608, filed Oct. 23, 1962, now abandoned.

The present invention provides shampoos that contain (a) A cationic compound containing at least one aliphatic hydrocarbon residue with more than 7, preferably 11 to 18, carbon atoms, as well as at least one 15 tertiary or quaternary nitrogen atom present in salt-like form, and

(b) A water-soluble reaction product of an alcohol with 6 to 11 carbon atoms having a branched hydrocarbon radical and whose main chain contains at least 5 20 carbon atoms, with up to 15 molecular proportions of ethylene oxide.

It is known to use in shampoos simultaneously cationic compounds and ethylene oxide adducts derived from linear higher fatty alcohols, for example n-dodecyl alcohol. Compared with such known shampoos the preparations of the invention are distinguished by a vastly superior 25 lathering power and stability of the lather.

The outstanding lathering power of the new shampoos is all the more surprising as the above-mentioned cationic components (a) and the non-ionic components (b) by themselves either have a completely inadequate or no lathering power at all on hair.

It is another surprising advantage of the preparations of the invention that their washing power is such that it ensures on one hand a completely adequate washing effect on dirty hair, while on the other hand this is not accompanied by an undesirable defatting, drying, irritation or the like of the hair or scalp respectively such as is connected with an excess washing effect.

The so-called "poissage-effect" which often occurs on application of shampoos containing cationic ingredients and which finds its expression in hair sticking together, more especially when it is subsequently rinsed, practically does not crop up with the present shampoos. It is another of their advantages that they have no unpleasant odour of their own or one that would render perfuming difficult.

Hair treated with one of the new shampoos has a soft, fluffy feel and a pleasing silky sheen, it has no electrostatic charge and is easy to brush and comb.

The afore-mentioned valuable properties of the hair are obtained more especially with those preparations of the invention which contain a hair shampoo preparation which contains

(1) As cation active component a member selected from the group consisting of (a) a tertiary amine salt of the compound of the formula

2

in which

n represents a number of at most 2,
 m represents a number of at most 3,
 R_1 represents an aliphatic hydrocarbon radical with 11 to 18 carbon atoms,

R_2 represents an alkene with 2 to 6 carbon atoms,
 R_3, R_4 and R_5 each represent a member selected from the group consisting of a hydrogen atom, an alkyl radical with at most 2 carbon atoms, a hydroxyalkyl radical with at most 3 carbon atoms, and the radical

where A and A' each represents a member selected from the group consisting of a hydrogen atom, the methyl radical and the hydroxyethyl radical with a cosmetically acceptable acid,

(b) A tertiary amine salt of a compound of the formula

in which R_1' represents an aliphatic hydrocarbon radical with 11 to 18 carbon atoms, and

R_2' represents a member selected from the group consisting of an alkylene radical containing 2 to 6 carbon atoms and the radical $\text{—CH}_2\text{—CHOH—CH}_2$, with a cosmetically acceptable acid,

(c) A quaternary ammonium salt of a compound of the formula set forth above under (a) and (b) with a member selected from the group consisting of methyl iodide, dimethyl sulfate, benzyl chloride, a polyglycol chloride containing at most 6 carbon atoms and ethylene chlorohydrine,

(d) A compound of the formula

in which

R_1'' represents a hydrocarbon radical with 11 to 18 carbon atoms, and

R_2'' represents a member selected from the group consisting of a hydrogen atom, a radical of the formula

and a radical of the formula

55 (2) As nonionic component a water-soluble reaction product of an alcohol which contains 6 to 11 carbon atoms, whose hydrocarbon radical is branched and whose

main-chain contains at least 5 carbon atoms, with at most 15 mols of ethylene oxide,

(3) Water, and

(4) A cosmetically acceptable acid in an amount which is sufficient to effect in the aqueous shampoo preparation a pH-value of 3.0 to 7.0, and in which shampoo preparation the weight ratio of component (1) to component (2) ranges from 1:1 to 1:100.

With regard to their non-ionic ingredient (2) those preparations of the invention deserve to be given preference which contain a compound obtained by reacting 5 to 10 molecular proportions of ethylene oxide with 1 molecular proportion of the alcohol referred to above under (2).

Particularly useful are those new mixtures whose non-ionic ingredient has been prepared by adding 5 to 10 molecular proportions of ethylene oxide on to a secondary or preferably primary aliphatic alcohol of the kind described above.

Surprisingly, it has further been found that those shampoos of the invention possess particularly good properties and are distinguished, for example, by the absence of an unpleasant odour of their own even when examined critically, which contain as the non-ionic ingredient an ethylene oxide adduct which, before being incorporated in the shampoo, has been subjected to a special purifying treatment, for example by expulsion of undesired substances by distillation. Such a purification operation may consist, for example, in the distillative expulsion from a commercial ethylene oxide adduct under a very good water-jet vacuum at about 160 to 180° C. or in a falling-film distillation. It has further been found that particularly valuable, purified products are obtained in this manner when the commercial ethylene oxide adduct liquefied by heating is mixed in the undiluted form with a sufficiency of an inorganic or organic acid to establish a weakly acidic reaction of the resulting solution of 10% strength. This may be achieved with concentrated acids, such as phosphoric acid of 85% strength, lactic acid of 90% strength, tartaric acid or citric acid. It is of special advantage to heat the batch to a distillation temperature corresponding to the boiling point of the monohydroxyethyl compound or of the monoglycol or diglycol ether of the alcohol selected as starting material.

The amine compound on which the cationic ingredient (a) is based can be prepared by methods known in the art from the corresponding amine bases or their reaction products with fatty acids or derivatives thereof, hydroxylalkylation agents, for example ethylene oxide, alkylating and acylating agents, for example chloracetic acid or with derivatives thereof, and then converted in known manner by reaction with acids into the amine salts or with quaternizing agents into the quaternary ammonium salts. Suitable starting materials for the manufacture of the cationic ingredient to be used according to the invention are tertiary amines of the formula

wherein R represents an alkyl with 12-16 carbon atoms, for example, N-dimethyl-dodecylamine, N-dimethyl-hexadecylamine and their hydroxylalkylation products, also diamines, for example N-dodecyl-ethylenediamine, tetramethylenediamine and hexamethylenediamine, N-octadecyl-ethylenediamine, N-dodecyl-propylenediamine, N-hexadecyl-propylenediamine and N-octadecyl-propylenediamine; also reaction products of such N-alkylene-polyamines with an alkylene oxide, such as ethylene oxide or propylene oxide, for example N-dodecyl-N:N'-dihydroxyethyl-ethylenediamine, N-dodecyl-N:N'-dihydroxyethyl-propylenediamine and N-octadecyl-N:N'-dihydroxyethyl-

propylenediamine. Furthermore, there may be used as starting material for the cationic ingredient (a) contained in the new preparations the following: mono-acylation products from 1 molecular proportion of a higher fatty acid (for example lauric, myristic, palmitic, stearic or oleic acid) and 1 molecular proportion of an alkylene-polyamine such as ethylenediamine or propylenediamine and diethylenetriamine; likewise suitable are reaction products of these monoacyl derivatives with a haloxydrin or alkylene oxide, such as N-lauroyl-N'-hydroxyethyl-ethylenediamine, N-palmitoyl-N'-hydroxyethyl-ethylenediamine, N-stearoyl-N'-hydroxyethyl-ethylenediamine, N-lauroyl-N'-hydroxyethyl-propylenediamine and N-lauroyl-hydroxyethyl-diethylenetriamine.

15 Those compounds of the general Formula 1, which are used in the form of their salts as cationic ingredient (a) of the new preparations and contain a radical of the formula

20 (in which formula A and A' have the above meanings) 25 are accessible by reacting the amine concerned with chloroacetic acid or with a compound of the general formula

30 (in which A and A' have the above meanings), more especially with chloracetamide or N:N-[di-(β -hydroxyethyl)]-chloracetamide.

35 The conversion of the selected tertiary amines into salts used as cationic ingredient of the new preparations is achieved by the usual formation of salts with cosmetically acceptable acids which may be inorganic, such as hydrochloric acid, and phosphoric acid, or organic acids as acetic acid, adipic acid, tartaric acid, malic acid, nitrile-triacetic acid, ethylenediamine-tetraacetic acid, citric acid, lactic acid, glycolic acid and mixtures of the above-mentioned acids. Quite generally speaking, any acid may be used that furnishes with the harmless amine salts that are neither toxic nor irritate the scalp, more especially the salts mentioned specifically below, such as are used in the present invention to establish the desired pH range.

40 To convert the tertiary amine compounds into quaternary ammonium compounds—which may likewise and with special advantages be used as cationic ingredient of the new preparations—they are reacted in known manner with a quaternizing agent, for example methyl iodide, dimethyl sulfate, benzyl chloride or with ethylene chloro-45 hydrin or with a polyglycol chloride.

45 It has further been found that the above-mentioned valuable properties of the new shampoos are particularly evident in those preparations in which the ratio of the cationic ingredient (a) to the non-ionic ingredient (b) ranges 50 from 1:1 to 1:30, preferably from 1:2 to 1:10. More especially at a ratio of (a):(b) of 1:3 it was found that the new preparations had surprisingly advantageous properties insofar as their lathering power and the stability of the lather, good washing power, gentleness towards the 55 skin and absence of the poissage-effect are concerned.

55 When the above-mentioned ratios are used, the new preparations have a particularly long shelf-life.

The preparations of the invention should have a moderately acidic to neutral reaction, for example ranging 60 from pH 3.0 to 7.0. The desired pH value may be adjusted with any inorganic or organic acidic compound acceptable for use in cosmetics, for example with acetic acid or phosphoric acid, or with acid phosphates, or adipic, tartaric, malic, nitrilotriacetic, ethylene-diamine-tetra-70 acetic, citric, lactic or glycolic acid.

Likewise suitable for this purpose are mixtures of inorganic and organic acids, for example mixtures of phosphoric acid and citric acid.

The new shampoos containing the new combinations are obtained by simply mixing and dissolving the ingredients, if desired with further addition of compounds conventionally contained in shampoos, such as perfume, dyestuffs, bleaching agents or thickening agents.

There may be further added fatty acid alkanol-amides, for example coconut oil fatty acid hydroxyethyl-amide. The new preparations may be prepared in solid, pasty or liquid form. They are applied in the known hairdressing manner.

Very favourable results were obtained with hair shampoos of the composition set forth above in this application, wherein the weight ratio of cation-active component (1) to nonionic component (2) ranges from 1:1 to 1:100.

Parts in the following examples are parts by weight.

Example 1

(a) The non-ionic polyglycol ethers listed in the following Tables I to V were examined for their lathering power. The results are shown in the tables under "Lather volume I."

(b) The cationic compounds listed in the following

Tables I to V were examined for their lathering power. The results are shown in the tables under "Lather volume II."

(c) Combinations of the cationic and non-ionic compounds shown in Tables I to V were examined for their lathering power. The results are shown in the tables under "Lather volume C."

The amounts of the ingredients making up the combinations are shown in the tables under "C"; "I" refers to the percentage of the non-ionic share of the total weight of the shampoo solution, and "II" refers to the cationic share of the total weight of the solution. The remainder of the total weight is accounted for by water and the amount of acid necessary to establish the pH value.

The shampoo solutions listed in the following Tables I, II and V were prepared by dissolving the non-ionic compound and the cationic compound in water with addition of a sufficiency of citric acid to establish a pH value of 4 to 4.5 of the individual solutions.

The term "lather volume" in the following Tables I to V refers to the amount of lather in cc. produced by twice washing 10 g. of homogeneously dirtied raw wool, moistened with 30 g. water at 35° C. with 2.7 cc. of the individual shampoo solution in each case. The indices "1" and "2" underneath "lather volume" in Tables I to V refer to the first and second wash each performed in the method employed for determining the lather volume.

TABLE I

The cationic compound used in the mixtures shown in Table I was obtained by heating the compound $C_{16}H_{33}N(CH_3)_2$ for 24 hours at 100° C. with excess

of 10% by weight of ethylene chlorohydrin above the stoichiometrically required amount.

Similar results are obtained by adjusting the combinations of Tables I to IIIb to a pH value from 4 to 4.5, instead of with citric acid, with one of the following acids: adipic, tartaric, phosphoric, lactic, acetic, ethylenediamine-tetraacetic, nitrilotriacetic or glycolic acid.

Similar, very advantageous results with regard to lathering power and washing power were obtained with aqueous solutions adjusted with citric acid to a pH value from 4 to 4.5, containing the following combinations of a non-ionic compound with a cationic compound:

(I) Non-ionic compound	(II) Cationic compound	(I) Non-ionic compound	(II) Cationic compound
2-ethylhexanol +10 mols of ethylene oxide		2-propylheptanol +5 mols of ethylene oxide.	
Isodecanol +5 mols of ethylene oxide		1-ethyl-, 3-ethyl-, 1-heptanol +8 mols of ethylene oxide.	
		2-ethylhexanol +5 mols of ethylene oxide.	Laurylamine +20 mols of propylene oxide.

The weight ratios between the component I and the component II are the same as those set forth above in Tables I to III.

TABLE IV.—EXAMPLES OF COMBINATIONS OF (a) AND (b) USING DIFFERENT ACIDS

	Share in percent of weight of the solution	Non-ionic compound I	Share in percent of weight of the solution	Cationic compound II	Share in percent of weight of the solution	Acid component III	Lather volume	
							C	1+II+III
							1	2

¹ With 2% coconut oil fatty acid ethanamide.

The following Table V shows that combinations in which the non-ionic ingredient is a compound derived from a linear alcohol or from a branched alcohol having

a side-chain of fewer than 5 carbon atoms or derived from an alkylphenol do not possess the advantageous properties of the preparations of the invention.

4	do	$\begin{array}{c} \text{CH}_3 \\ \\ \text{C}_{16}\text{H}_{33}\text{N}-\text{CH}_2\text{CH}_2\text{OH}]^+ \text{Cl}' \\ \\ \text{CH}_3 \end{array}$	A reaction product of 1 mol coconut oil fatty acid and 2 mols diethanolamine, with elimination of 1 mol water.	12 4 5	64

Mixtures having very valuable properties are also obtained by adding 2%, 4% and 8% of polyvinylpyrrolidone (molecular weight 400,000 to 700,000).

Example 3

The shampoos listed in Tables I to IV of Example 1 were examined as to whether they displayed the so-called pisseffect. As is known, this effect consists in the following: When hair washed with a shampoo containing a cationic compound and then rinsed with water, salve-like, water-insoluble deposits form on the hair and, more especially in the case of women's long hair, cause it to stick. The occurrence of this sticking effect ("pisse") seems to be due to the anionic constituents of the dirt found on human hair.

In the in vitro tests 18 g. of hair dirtied with 10% of oleic acid was washed in each case with 5 g. of the shampoos listed in the Tables I to IV and then rinsed. It was found that after washing at 35° C. and rinsing, the combinations listed in Tables I to IV produced substantially no sticking of the hair.

(a) The non-ionic polyglycol ether, listed in the following Tables VIII to X, was freed in a falling-film evaporator from the unreacted alcohol and the monoglycol and diglycol ethers and then examined for its lathering power. The results are shown in the Tables VIII to X under the heading "Lather volume I."

(b) The cationic compounds listed in the following Tables VIII to X were examined for their lathering power. The results are shown in the Tables VIII to X under the heading "Lather volume II."

(c) The combinations of cationic compound and non-ionic compound listed in the Tables VIII to X were examined for their lathering power. The result is listed in Tables VIII to X under "Lather volume C." The amounts of the ingredients are shown in the Table under "C," in which "I" is the percentage share of the non-ionic compound of the total weight of the shampoo solution, and "II" is that of the cationic compound. The remainder of the total weight is accounted for by water and the amount of acid needed to adjust the pH value.

TABLE VIII

	Non-ionic compounds	Lather volume I		Cationic compounds containing a quaternary nitrogen atom		Lather volume II		C I+II	Lather volume C	
		1	2			1	2		1	2

The shampoos set forth above in Tables VIII and IX were adjusted with citric acid to a pH-value of 4.0 to 4.5, with the exception of those signified by (+) which were adjusted with citric acid to pH-value of 6.9.

Good results were also obtained with shampoos of the compositions set forth above in Tables I to IV and VI to IX when the nonionic (1) and the cationic (2) compounds were used in weight proportions different from those set forth specifically in the said tables but lying within the range of 2:1 to 10:1.

Example 5

(a) The following mixture was prepared:

4 parts of a mixture of 1 mol of coconut fatty acid diethanolamide and 1 mol of diethanolamine, 15
 25 parts of a condensatoin product containing 1 mol of 2-ethylhexanol and about 8 mols of ethylene oxide, 20
 0.25 part of cetyltrimethyl-(2-hydroxyethyl)-ammonium chloride, 25
 2.5 parts of about 88% lactic acid, 3 parts of polyethylene glycol having a molecular weight of about 20,000.

The mixture was made up to 100 parts with water and a shampoo obtained to which perfumes can be added, if desired.

What is claimed is:

1. A hair shampoo preparation which consists essentially of

(1) the cationic compound of the formula

(2) a nonionic water-soluble reaction product of a saturated branched-chain alcohol with 6 to 11 carbon atoms, whose main-chain consists of at least 5 carbon atoms, with 5 to 15 mols of ethylene oxide, 40
 (3) water, and 45
 (4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof, in an amount which is sufficient to effect in the aqueous shampoo preparation a pH-value of 3.0 to 7.0, and in which shampoo preparation the weight ratio of component (1) to component (2) ranges from 1:1 to 1:100.

2. A hair shampoo preparation which consists essentially of

(1) a cationic compound of the formula

wherein n represents a number from 2 to 6 and X^- represents a halogen anion selected from the group consisting of chlorine and bromine, 60
 (2) a nonionic water-soluble reaction product of a saturated branched-chain alcohol with 6 to 11 carbon atoms, whose main-chain consists of at least 5 carbon atoms, with 5 to 15 mols of ethylene oxide, 65
 (3) water, and 70
 (4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof in an amount which is sufficient to effect in the aqueous shampoo preparation a pH-value of 3.0 to 7.0, and in which shampoo preparation the weight ratio of component (1) to component (2) ranges from 1:1 to 1:100.

3. A hair preparation which consists essentially of

(1) a tertiary amine salt of a cationic compound of the formula

wherein R represents alkyl with 12 to 16 carbon atoms with a cosmetically acceptable acid selected from the group consisting of acetic acid, phosphoric acid, adipic acid, tartaric acid; malic acid, nitrilotriacetic acid, ethylenediamine-tetraacetic acid, citric acid, lactic acid, glycolic acid and mixtures thereof,

(2) a nonionic water-soluble reaction product of a saturated branched-chain alcohol with 6 to 11 carbon atoms, whose main-chain consists of at least 5 carbon atoms, with 5 to 15 mols of ethylene oxide,

(3) water, and

(4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof, in an amount which is sufficient to effect in the aqueous shampoo preparation a pH-value of 3.0 to 7.0,

and in which shampoo preparation the weight ratio of component (1) to component (2) ranges from 1:2 to 1:100.

4. A hair shampoo preparation which consists essentially of

(1) a tertiary amine salt of the cationic compound of the formula

with a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof,

(2) a nonionic water-soluble reaction product of a saturated branched-chain alcohol with 6 to 11 carbon atoms, whose main-chain consists of at least 5 carbon atoms, with 5 to 15 mols of ethylene oxide,

(3) water, and

(4) a cosmetically acceptable acid selected from the group consisting of acetic acid, phosphoric acid, adipic acid, tartaric acid, malic acid, nitrilotriacetic acid, citric acid, lactic acid, glycolic acid and mixtures thereof, in an amount which is sufficient to effect in the shampoo preparation a pH-value of 3.0 to 7.0,

and in which shampoo preparation the weight ratio of component (1) to component (2) ranges from 1:1 to 1:100.

5. A hair shampoo preparation which consists essentially of

(1) a tertiary amine salt of the cationic compound of the formula

with a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof,

(2) a nonionic water-soluble reaction product of a saturated branched-chain alcohol with 6 to 11 carbon

23

atoms, whose main-chain consists of at least 5 carbon atoms, with 5 to 15 mols of ethylene oxide,

- (3) water, and
 (4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycollic acid and mixtures thereof, in an amount which is sufficient to effect in the aqueous shampoo preparation a pH-value of 3.0 to 7.0, and in which shampoo preparation the weight ratio of component (1) to component (2) ranges from 1:1 to 1:100.

6 A hair shampoo preparation which consists essen-

6. A hair shampoo preparation which consists essentially of

- (1) a tertiary amine salt of the cationic compound of the formula

2
with a cosmetically acceptable acid selected from the
group consisting of acetic acid, phosphoric acid,
adipic acid, tartaric acid, malic acid, nitrilotriacetic
acid, ethylenediamine-tetraacetic acid, citric acid,
lactic acid, glycolic acid and mixtures thereof,
(2) a nonionic water-soluble reaction product of a
saturated branched-chain alcohol with 6 to 11 car-
bon atoms, whose main-chain consists of at least 5
carbon atoms, with 5 to 15 mols of ethylene oxide,
(3) water, and
(4) a cosmetically acceptable acid selected from the
group consisting of acetic acid, phosphoric acid,
adipic acid, tartaric acid, malic acid, nitrilotriacetic
acid, ethylenediamine-tetraacetic acid, citric acid,
lactic acid, glycolic acid and mixtures thereof, in
an amount which is sufficient to effect in the aqueous
shampoo preparation a pH-value of 3.0 to 7.0,
and in which shampoo preparation the weight ratio of
component (1) to component (2) ranges from 1:1 to
1:100.

7. A hair shampoo preparation which consists essentially of

- (1) a tertiary amine salt of the cationic compound of the formula

with a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycollic acid and mixtures thereof,

(2) a nonionic water-soluble reaction product of a saturated branched-chain alcohol with 6 to 11 carbon atoms, whose main-chain consists of at least 5 carbon atoms, with 5 to 15 mols of ethylene oxide,

(3) water, and

(4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycollic acid and mixtures thereof, in an amount which is sufficient to effect in the aqueous shampoo preparation a pH-value of 3.0 to 7.0, and in which shampoo preparation the weight ratio of component (1) to component (2) ranges from 1:1 to 1:100.

24

8. A hair shampoo preparation which consists essentially of

- (1) a tertiary amine salt of the cationic compound of the formula

with a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof,

- (2) a nonionic water-soluble reaction product of a saturated branched-chain alcohol with 6 to 11 carbon atoms, whose main-chain consists of at least 5 carbon atoms, with 5 to 15 mols of ethylene oxide.

- (3) water, and
(4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycollic acid and mixtures thereof, in an amount which is sufficient to effect in the aque-

ous shampoo preparation a pH-value of 3.0 to 7.0, and in which shampoo preparation the weight ratio of component (1) to component (2) ranges from 1:1 to 1:100.

9. A hair shampoo preparation which consists essentially of

- (1) a tertiary amine salt of the cationic compound of the formula

wherein n represents a whole number of at most 2, with a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof.

- (2) a nonionic water-soluble reaction product of a saturated branched-chain alcohol with 6 to 11 carbon atoms, whose main-chain consists of at least 5 carbon atoms, with 5 to 15 mols of ethylene oxide,

- (3) water, and
(4) eventually to take up the task of

- (4) a cosmetically acceptable acid selected from the group consisting of acetic acid, phosphoric acid, adipic acid, tartaric acid, malic acid, nitrilotriacetic acid, ethylenediamine-tetraacetic acid, citric acid, lactic acid, glycolic acid and mixtures thereof, in an amount which is sufficient to effect in the aqueous shampoo preparation a pH-value of 3.0 to 7.0,

and in which shampoo preparation the weight ratio of component (1) to component (2) ranges from 1:1 to 1:100.

100.
10. A hair shampoo preparation which consists essentially of
(1) A hair shampoo base.

- a cationic compound selected from the group consisting of

in which n represents a number of at most 2, m represents a number of at most 3, R_1 represents alkyl with 11 to 18 carbon atoms, R_2 represents alkylene with 2 to 6 carbon atoms, R_3 , R_4 and R_5 each represent a member selected from the group consisting of hydrogen, alkyl with at most 2 carbon atoms, hydroxyalkyl with at most 3 carbon atoms,

where A and A' each represents a member selected from the group consisting of hydrogen, methyl and hydroxyethyl, with a cosmetically acceptable acid selected from the group consisting of acetic acid, phosphoric acid, adipic acid, tartaric acid, malic acid, nitrilotriacetic acid, ethylene-diamine-tetraacetic acid, citric acid, lactic acid, glycolic acid and mixtures thereof, and

- (b) a quaternary ammonium salt of a compound of the formula set forth above under (a) with a member selected from the group consisting of methyl iodide, dimethyl sulfate, benzyl chloride, a polyglycol chloride containing at most 6 carbon atoms and ethylenechlorohydrine,
 (2) a nonionic watersoluble reaction product of a saturated branched-chain alcohol with 6 to 11 carbon atoms, whose main-chain consists of at least 5 carbon atoms, with 5 to 15 mols of ethylene oxide,
 (3) water, and
 (4) a cosmetically acceptable acid, as defined above in this claim under (a) in an amount which is sufficient to effect in the aqueous shampoo preparation a pH-value of 3.0 to 7.0,

and in which shampoo preparation the weight ratio of component (1) to component (2) ranges from 1:1 to 1:100.

11. A hair shampoo preparation which consists essentially of

- (1) a cationic quaternary ammonium salt of a compound of the formula

wherein R represents alkyl with 11 to 18 carbon atoms and R_2 and R_3 represents alkyl with at most 2 carbon atoms with ethylenechlorohydrine,

5

10

15

25

30

40

45

50

(2) a nonionic water-soluble reaction product of a saturated branched-chain alcohol with 6 to 11 carbon atoms whose main-chain consist of at least 5 carbon atoms, with 5 to 15 mols of ethylene oxide,

(3) water, and

(4) a cosmetically acceptable acid as defined above in claim 10 under (a) in an amount which is sufficient to effect in the aqueous shampoo preparation a pH value of 3.0 to 7.0,

and in which shampoo preparation the weight ratio of component (1) to component (2) ranges from 1:1 to 1:100.

12. A preparation as claimed in claim 10 which contains as further component approximately 5% by weight of a mixture of coconut fatty acid diethanolamide and diethanolamine.

13. A preparation as claimed in claim 10 which contains as a further component an effective amount of a mixture of coconut fatty acid diethanolamide and diethanolamine as a thickening agent.

14. A preparation as claimed in claim 10 which contains as a further component approximately 1-20% by weight of a thickening agent.
